ELECTRIC SNAP SWITCH

Edwin August Miller, Fairfield, Conn.

Application January 21, 1948, Serial No. 3,525

1 Claim. (Cl. 200—67)

1

This invention relates to actuator control of switch blades, and more particularly to blades of cantilever type.

The objects of the invention are to provide, for a cantilever tension blade, an actuator controlling upper and lower positions of rear extremity of said blade; to provide for a tension blade an actuator movement that longitudinally shifts the blade; and to provide for tension blade a forwardly spring pressure means against which the movement of actuator to normal position is made.

Referring to the accompanying drawing, the Figure 1 is an upright elevation of the device illustrating the actuator and parts controlled thereby in one position; Figure 2 is a similar elevation but illustrating the actuator and controlled parts in a different position; Figure 3 is a plan view of the tension member; Figure 4 is a plan view of the base of the device; Figure 5 is an upright elevation of a slightly modified form of device, and Figure 6 is a detail of further modification.

With more particular reference to the accompanying drawing, the numeral 1 designates the base of the device having the terminals 2, 3, and 4 depending therefrom. Secured to the upper surface 5 of the base 1 are upright supports 6 and 7 providing interfacing and relatively spaced stops 9 and 10, respectively. The support 8 is pivotally provided with the rocking actuator 11 having an arm 12 extending rearwardly of the support 8 and having a downwardly bent extremity 13 carrying within passage 14B the rear extremity 14 of the tension member 15.

A compression member 16 is carried by the free extremity 17 of the tension member 15, the tension member 15 having an elongated opening 18 therethrough.

Upper and lower contacts 19 and 20, respectively, are carried by said free extremity 17 of the tension member 15 for movement therewith between spaced stops 9 and 10.

Secured upon the base 1 at the support 8 is a spring 21 having an extremity 22 carrying the free extremity 23 of the compression member 16 thereby normally positioned above the tension member 15.

To operate, force is applied, manually or otherwise, to press the actuator 11, thereby tilting the actuator 11 upon the upright support 8. Such applied force causes the bent extremity 13 to move upwardly carrying therewith the rear extremity 14 of the tension member 15 above the extremity 23 of the compression member 16 and

so relatively changing the positions of said members 15 and 16 that the tension member becomes distorted. Upon the sudden release of the distorted condition of the tension member 15 the free extremity 17 thereof is rapidly moved with a snap-action from engagement of the contact 20 with the stop 10 and into a wiping engagement of the contact 19 with the stop 9.

10 A return of the actuator 11 to its normal position causes a reversed movement of the several parts of the device with a snap-action of a return movement of the free extremity 17 of the tension member 15.

15 It is to be understood that the longitudinal shifting movement of the tension member 15 is due to the arc of movement of the bent extremity 13 having a center 25 upon which the actuator 11 pivots within the passage 25A.

20 The Figure 5 illustrates a slight modification of the preferred form of the device. In the modified device, the forwardly spring pressure against the tension member 15A is accomplished by means of spring pressure against the rear extremity 14A of the tension member 15A which is freely engaged within a passage 14B provided by the bent extremity 13A of the actuator 11, the free extremity 23A of the compression member 16A being held by the support 8A. In other words, the shifting force of the switch blade in the modified form is provided by the spring 21A directly engaging the tension member 15A, while in the preferred form the shifting force is provided by the spring 21 engaging the free extremity 23 of the compression member 16. In operation, the results in both forms of the device are practically similar.

25 The Figure 6 is a further modification wherein both of the springs 21, of the preferred form, and 21A of the modified form of the Figure 5, are employed. Each spring 21 and 21A serves as a strut holding apart certain members of the device as, with respect to the spring 21, the compression member extremity 23 from the rigid support 8, and with respect to the spring 21A, the tension member extremity 17 from the bent extremity 13 of the actuator 11.

I claim:

30 A switch blade device having a base and comprising a tension member; upper and lower contacts with which the free extremity of said member is provided for movement between relatively spaced stops; a rigid upright support rigidly mounted upon said base; an upright cantilever spring mounted upon said base and having a notched-like free end adjacent said upright sup-

port; a compression member carried by the said free extremity of said tension member, said compression member having a free extremity pivotally carried by said notched-like extremity of said cantilever spring for relatively passing the free extremity of said compression member past said tension member; a rocking actuator having a limited sliding movement within an opening provided by said upright support, said actuator having a rear extremity pivotally carrying the rear extremity of said tension member; said normally located pivot-point at the free extremities of said compression member and said cantilever spring being adapted to shift along a divagating arc upon the sliding pivotal movement of said actuator within said support opening and thus adapted

to provide a quick snap-action of said blade for a given degree of actuation.

EDWIN AUGUST MILLER.
